CLAIM

The ornamental design for a bin, as shown.

DESCRIPTION

FIG. 1 is a perspective view from the front and to one side of a bin embodying the design;

FIG. 2 is a perspective view from the rear end and to one side of the bin shown in FIG. 1;

FIG. 3 is a front elevation of the bin shown in FIG. 1;

FIG. 4 is a right side elevation of the bin shown in FIG. 1;

FIG. 5 is a left side elevation of the bin shown in FIG. 1;

FIG. 6 is a rear elevation of the bin shown in FIG. 1;

FIG. 7 is a top plan view of the bin in FIG. 1;

FIG. 8 is a bottom plan view of the bin in FIG. 1;

FIG. 9 is a perspective view from the front and to the right side of the bin shown in FIG. 1, with lid removed;

FIG. 10 is a top plan view of the bin shown in FIG. 1, with lid removed; and,

FIG. 11 is a plan view of the lid of the bin shown in FIG. 1.

The appearance of the lid of the bin, as seen from below, does not comprise part of the claimed design.
